UNITED STATES PATENT OFFICE.

ALEXANDER BOURASSA, OF CHICAGO HEIGHTS, ILLINOIS.

RAIL-JOINT.

1,112,670.

Specification of Letters Patent.

Patented Oct. 6, 1914.

Application filed November 28, 1913. Serial No. 803,395.

To all whom it may concern:

Be it known that I, ALEXANDER BOURASSA, a citizen of the United States, and a resident of the town of Chicago Heights, in the county of Cook and State of Illinois, have invented certain new and useful Improvements in Rail-Joints; and I do hereby declare that the following is a full, clear, and exact description of the same, reference being had to the accompanying drawings, and to the numerals of reference marked thereon, which form a part of this specification.

A number of joints have been devised for the purpose of maintaining rails connected to one another in proper alinement on a road bed, but many of such devices have been impractical, owing to complication of parts or due to the expense involved in other ways.

This invention relates to a rail-joint which is exceedingly simple in operation and consists of only a few parts, which serve to lock the rail ends rigidly together substantially as a unitary structure, and acting further to reinforce and support the rails at the joint.

It is an object of this invention to construct a rail-joint wherein one wedge member engages beneath the heads of the abutting rails and a second wedge member co-operatively engaging said first member, bears upon the upper surface of the flanges of said rails to tighten each of said wedge members in position between the heads and flanges of said rails.

It is also an important object of my invention to construct a rail joint embracing co-operative wedge members adapted to engage one another between the head and flange of two abutting rails, together with means preventing lateral movement of said wedge members from the rails.

It is also an object of this invention to construct a rail-joint wherein co-operative wedge members are mounted on the inner and outer sides of the webs of two abutting rails with certain of said wedge members engaged beneath and contacting the heads of said rails, and certain other wedge members co-operatively engaged therewith and contacting the flanges of said rails, and with means extending through apertures in the webs of said rails to prevent lateral movement of said first mentioned web members.

It is also an object of this invention to construct a rail-joint in which wedge splice

bars are held beneath the heads of abutting rails by bolts extending through apertures in the webs of said rails, and with slideable grooved wedge bars adapted to be driven beneath said wedge members to tighten the same against the rails, said latter bars also serving as a lock for the bolts.

It is furthermore an object of this invention to construct a rail-joint wherein co-operative wedge members interfitting with one another are engaged in wedging relation between the heads and flanges of abutting rails and with slots cut in certain of said wedge members to permit engagement thereof over lateral retaining means extending through the web of the rails.

It is finally an object of this invention to construct a simple, durable rail-joint consisting of few parts wherein co-operative wedges act to lock one another in position, so that looseness occasioned by wear may be readily taken up by a few blows upon certain of said wedge members.

The invention (in a preferred form) is illustrated in the drawings and hereinafter more fully described.

In the drawings: Figure 1 is a fragmentary side elevation of the abutting ends of two rails joined together by a device embodying the principles of my invention. Fig. 2 is a top plan view thereof. Fig. 3 is a section on line 3—3 of Fig. 1, with parts in elevation. Fig. 4 is a view similar to Fig. 3, of a modification of my invention. Fig. 5 is a section on line 5—5 of Fig. 4.

As shown in the drawings the reference numeral 1, indicates a head of a rail which is joined to a base 2, of the rail, as is usual, by means of a web 3. Fig. 1 clearly illustrates two rails abutting one another, and held in position by members constituting my invention. For the purpose of locking the abutting ends of the rails together I provide relatively long wedge members or splice bars 4, which are thickened along their upper edge or that engaging beneath the head of the rail, and are tapered along the bottom edge, so that the bar decreases in depth from one end to the other. As clearly shown in Fig. 3, two such splice bars 4, are provided, one on each side of the webs of the respective rail ends, and bolts 5, with an adjusting nut 6, thereon, extend through registering apertures in said splice bars and the webs 3, of the rails. Wedge bars 7, are provided to co-operate with said splice bars 4,

said wedge bars comprising a relatively long bar of metal, having a groove of increasing depth extending longitudinally therein to receive the lower margin of said splice bar 5 therein, and on its under face said bar 7, is angled in conformity with the inclination of the upper surface of the flange of the rail.

In the modification illustrated in Fig. 4, splice bars 8, are provided to close on each 10 side of the respective rails beneath the heads thereof, as before described, but in place of apertures, said splice bars are provided with slots 9, extending upwardly from the lower edge of the splice bar to about the middle 15 thereof. In this construction a double headed rivet or bolt 10, is used, which extends through an aperture 11, in the web of the rail, said aperture being sufficient in size to admit insertion of the head of the bolt there- 20 through. Grooved wedge members 7, are provided as before, and of course the varying depth of the grooves and the taper of the splice bars permits a wedging action be- 25 tween the splice bars and the wedge bars.

25 The operation is as follows: In connecting the rail ends, as shown in Figs. 1, 2, and 3, the splice bars 4, are set up beneath the heads of the respective rail ends and the bolts 5, inserted therethrough, the wedge 30 bars 7, are then driven inwardly beneath the splice bars with the splice bars fitting in the grooves in the respective wedge bars. The required tightness of the parts is attained by driving the wedge bars inwardly the amount 35 desired, and it is to be noted in this connection that said wedge bars engage beneath the squared heads of the bolts and nuts respectively, thus providing a lock for the nut to prevent loosening thereof. In the con- 40 struction illustrated in Figs. 4 and 5, the double headed bolts 10, are first inserted through the apertures in the rail webs and the splice bars are then dropped over the bolts and moved into a position beneath the 45 head of the rail, after which the wedge bars 7, are driven in to tighten the same. It is clear that the stress upon the respective bolts 5, and 10, is not very great, merely an amount sufficient to prevent lateral dis- 50 placement of the wedge members as they are driven into engagement with one another, and this is dependent upon the inclination of the top surface of the rail base. The engagement of the splice bars and 55 wedge bars with one another between the heads and bases of the rails, owing to the wedging action, affords an exceedingly stiff joint. Obviously my invention is extremely practical, inasmuch as a track walker in- 60 specting the rails, upon finding a loose joint occasioned by wear, may, with a few blows upon the wedge bar, easily tighten up the joint.

I am aware that various details of construction may be varied through a wide

range without departing from the principles of this invention. I therefore do not pur- 70 pose limiting the patent granted otherwise than necessitated by the prior art.

I claim as my invention:

75 1. A rail-joint comprising slotted wedge members having bands thereon adapted to be inserted beneath the heads of abutting rails, grooved wedge bars engaging the lower edges of said wedge members and resting upon the flanges of the rails, and means 80 engaging in the slots and extending through apertures in the web of a rail acting to prevent lateral displacement of said wedge members.

85 2. In a device of the class described co- operative inter-fitting wedge members en- gaged between the heads and flanges of abutting rails, certain of said wedge mem- bers provided with slots therein and bolts 90 engaging in the slots and extending through the apertures of the web of a rail to prevent lateral displacement of said wedge members.

95 3. In a device of the class described co- operative wedge members engaging between the heads and flanges of abutting rail ends, certain of said members having vertical slots 100 therein and bolts extending through apertures in the web of the rails and said slotted wedge members to prevent lateral displace- 95 ment of the latter.

100 4. In a device of the class described co- operative oppositely disposed wedge mem- bers engaged between the heads and flanges of abutting rail ends on the inner and outer 105 side of the rails respectively, certain of said members having open slots therein extend- ing from the edge of the wedge member to near the middle thereof and other of said members provided with grooves to receive 110 the lower edge of said slotted members, and a plurality of bolts engaging in the slots and extending through enlarged apertures in the rail web to hold said oppositely dis- 115 posed slotted wedge members from lateral displacement independently of other con- nection with the rails, the enlarged apertures in said rail web permitting the insertion of the bolt heads therethrough in as- sembling.

120 5. In a device of the class described ta- pered splice bars having vertically extended slots therein and adapted to engage beneath the heads on each side of a rail, grooved wedge bars adapted to receive said splice bars therein, said bars acting to wedge one another between the heads and flanges of the respective rails, and one piece double headed bolts releasably connecting the splice bars by engagement in the vertical slots and 125 extending through apertures in the web of a rail.

130 6. In a device of the class described ta- pered slotted splice bars adapted to be en- gaged longitudinally beneath the heads of

abutting rail ends, double headed bolts releasably connected to said splice bars by engagement in the slots therein, and wedge members adapted to be driven between the 5 tapered edge of said splice bars and the base of the rail to rigidly engage said splice bars and wedge bars in position.

In testimony whereof I have hereunto subscribed my name in the presence of two subscribing witnesses.

ALEXANDER BOURRASSA.
